INVENTOR
FREDERICK FOURNIER
BY Chas E. Fournier

ATTORNEY.

UNITED STATES PATENT OFFICE.

FREDERICK FOURNIER, OF SAN FRANCISCO, CALIFORNIA.

WINDOW ADJUSTER.

1,422,552.

Specification of Letters Patent.

Patented July 11, 1922.

Original application filed February 25, 1920; Serial No. 361,127. Divided and this application filed March 9, 1921. Serial No. 451,036.

To all whom it may concern:

Be it known that I, FREDERICK FOURNIER, a citizen of the United States, residing at the city and county of San Francisco and State of California, have invented new and useful Improvements in Window Adjusters, of which the following is a specification.

This invention relates to a window adjuster, and the present application is a division of an application entitled "Window construction," filed February 25, 1920, Serial No. 361,127.

It is the principal object of the present invention to provide a window construction especially adaptable to casement windows whereby the window may be securely locked or may be swung to any intermediate position from closed to full open and locked against movement in this position, the mechanism comprising swinging and locking means.

The present invention contemplates the use of a worm-operated swinging arm adapted to be slidably and detachably secured to a guide rail of a window frame and when operated to swing the window in or out as the case may be and lock the window against movement in an intermediate position. The construction also provides a floating hinge for the window whereby the entire frame may be moved across the window or reversed.

The invention is illustrated by way of example in the accompanying drawings, in which:

Fig. 1 is a fragmentary view in perspective illustrating the swinging and lock mechanism with which the present invention is concerned.

Fig. 2 is a view in horizontal section disclosing other details of the present invention.

Fig. 3 is a fragmentary view in perspective illustrating the detachable connection between the swinging arm, its slide and the guide rail.

In the drawings, 10 indicates a window frame provided with hinge plates 11. These plates are disposed at the top and bottom of one of the stiles of the frame and are fitted with a vertical hinge rod 12.

The present invention is not particularly concerned with the hinge construction but with swinging and locking means for the window.

The swinging means comprises a lever arm 16 which is mounted upon a pivot screw 17. The lever arm projects outwardly from a pocket 18 in the window sill, this pocket being preferably covered by a plate 19. The arm as shown in Fig. 1 is formed with an enlarged base portion of semi-circular shape, a plurality of gear teeth 19 occur along the transverse of this portion and are adapted to be in constant mesh with a worm gear 20 mounted within bearings 22. These bearings are carried upon a base plate 23 which is secured to the floor of the pocket. The end of the worm gear is formed with a hub 24 extending through the inner face of the sill and adapted to receive a turning crank 25. This crank may be detachably secured to the hub and carries a pin to seat within a transverse slot 26 whereby rotation of the crank will produce unison movement of the gear. The outer end of the arm 16 is formed with a single opening to receive a pin 27 as indicated in Fig. 5. This pin is carried upon a sliding block 28, the block being preferably of T-section. The base of this block or the flanged portion extends along a guide rail 29. This rail is channel-shaped with the legs of the channel section bent over to provide retaining flanges. A lock finger 30 is pivoted to the block 28 by a screw 31 and is intended to normally swing over the top of pin 27 to prevent the accidental movement of the arm from engagement with the pin. It will thus be evident that swinging movement of the arm will cause sliding movement of the block 28 along the rail and this combined action will in turn cause the window 10 to swing on its hinge pivot. It will be seen that due to the pitch of the threaded worm and the teeth 19 in engagement therewith the window will be locked against inward or outward movement when pressure is exerted upon the window or the arm.

In operation of the present invention the window may be swung to any angle desired by rotation of the worm 20 through the medium of the crank 25. When the worm is rotated to swing the arm 16 outwardly, a force will be exerted against the sliding block 28. This will swing the window at the same time causing the block to slide along the guide rail 29. This sliding action will be, of course, determined by the distances between the swinging center of 110

the arm and the hinge of the window. When the window has been swung to a desired position the worm gear 20 will act to lock the arm against rotation and will 5 securely hold the window to prevent it from being either opened or closed. The numeral 33 indicates a conventional latch which co-operates with the plate 32 for locking the window when the latter is 10 closed.

It will thus be seen that the construction here shown provides simple means whereby a casement window may be swung open to a desired angle and locked or by 15 which it may be closed and positively locked.

While I have shown the preferred form 20 of my invention as now known to me it will be understood that various changes in the combination, construction and arrangement of parts may be made by those skilled in the art without departing from the spirit 25 of the invention as claimed.

Having thus described my invention, 25 what I claim and desire to secure by Letters-Patent is—

1. The combination with a framed opening and a swinging closure therefor mounted to swing about vertical supports, of an 30 operating mechanism for said closure comprising a pivoted operating lever, a guide track carried by said closure adjacent the bottom thereof, a sliding block engageable with the guide track and adapted to be detachably connected to the operating lever and a keeper plate pivotally mounted on the sliding block for retaining the operating lever in connection with the sliding block.

2. In combination with a framed opening and a reversible swinging closure there- 40

for of an operating mechanism for said closure comprising a recess in the bottom of said framed opening, a worm mounted in said recess, a pivoted operating arm having a toothed segmental end in engagement 45 with the worm, operating means for actuating the worm so as to swing the arm, a guide track secured to the lower end of the closure, a T-shaped sliding block having its base engaging the guide track, a pin 50 secured to the sliding block and adapted to connect the same and the free end of the operating lever, a keeper plate pivotally mounted on the block and adapted to secure the free end of the operating lever on 55 the pin or to allow the lever to be removed from the pin when desiring to reverse the closure.

3. In combination with a frame opening having a swinging closure therefor and a worm mechanism having an operating arm for adjusting the window of a connecting mechanism interposed between the free end of the operating arm and the swinging closure, the said connecting mechanism comprising a channel shaped guide secured to to the lower end of the closure and having its flanges inturned to form retaining fingers, a T-shaped sliding block having its base positioned within the guide and its 60 body portion extending therefrom, a vertically extending pin secured to the T-shaped member, adapted to engage an aperture in the free end of the operating arm, a pivoted keeper plate so positioned that it 65 may be swung to retain the arm end in engagement with the pin or allow the same to be instantly removed from the pin.

FREDERICK FOURNIER.
